HIGHWAY CROSSING SIGNAL

Marcian A. Scheg, Rochester, N.Y., assignor to General Signal Corporation, Rochester, N.Y.

Filed Sept. 19, 1962, Ser. No. 71,785

Term of patent 14 years

(Cl. D72—1)

FIG. 1 is a front elevational view of a highway crossing signal showing my new design;

FIG. 2 is a side elevational view thereof; and

FIG. 3 is a reduced rear elevational view thereof.

The dominant features of my design resides in the full line portions of the drawing with a fragmentary post and clamps shown in broken lines for illustrative purposes only.

I claim:

The ornamental design for a highway crossing signal, as shown and described.
